Primary Examiner — Gino Colan(74) *Attorney, Agent, or Firm* — Brinks Gilson & Lione(57) **CLAIM**

We claim the ornamental design for a barrow cart, as shown and described.

DESCRIPTION

FIG. 1 is a top perspective view of a barrow cart showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof; and,

FIG. 7 is a right side elevation view thereof.

The broken lines in FIG. 1 and 3-7 illustrate portions of the barrow cart that form no part of the claimed design. The barrow cart is shown with symbolic breaks. The appearance of any portions of the barrow cart between the break lines forms no part of the claimed design.
